UNITED STATES PATENT OFFICE.

JOSEPH ROSAY, OF NEW YORK, N. Y.

DRINKING ATTACHMENT FOR WATER FAUCETS.

Application filed August 18, 1926. Serial No. 130,091.

This invention relates to a drinking attachment for water faucets; and has for its object to provide a drinking attachment of this character constructed of a short length 5 of tubing with its ends offset preferably to form somewhat of a U-shape. One end of the tubing is arranged to fit loosely into a faucet and provided with resilient means to grip the same and support the drinking end of the 10 tube in operating position.

With these and other objects in view, the invention consists of certain novel features of construction, as will be more fully described, and particularly pointed out in the 15 appended claims.

In the accompanying drawings:

Figure 1 is a side elevation partly in section showing my improved drinking device as attached to a water faucet.

Figure 2 shows a cup member as detachably connected to the drinking end of the tube to retain the water discharged from the drinking end of the tube.

Figure 3 is a side elevation of this cup.

Figure 4 is a modification illustrating the spring on the end of the tube as arranged to fit inside of the faucet to support the tube in operating position.

This invention provides a sanitary drinking device which may be attached to any ordinary water faucet for the purpose of directing a portion of the water from the faucet in an upward direction and in a position to be readily employed for drinking purposes, the 30 device being extremely inexpensive to construct and one which may be as readily detached from the faucet and carried about in the pocket of the user. Also in some instances, it is found of advantage to provide

a cup member which may be readily detachably connected to the discharge end of a tube which is adapted to hold a body of water and so control in a measure the height of the discharging flow of the water from the tube 45 to render it easier to drink therefrom; and the following is a detailed description of one embodiment of my invention by means of which these advantageous results may be accomplished.

With reference to the drawings, 10 designates the usual water faucet which is ordinarily turned downwardly and 11 the controlling handle therefor.

My improved drinking device is preferably formed of a short length of rigid tubing 12 with its ends offset or turned at sub-

stantially a right angle to the body of the tubing to form a substantially U-shaped device, the tube being preferably of a diameter considerably less than the inner diameter of the usual faucet to which it is adapted to be attached. One end 13 of the tubing is arranged to extend up into the faucet and a short spring finger 14 which may be of the flat metal type may be soldered or riveted as 60 at 15, to the wall of the tubing to extend upwardly along the upturned end 13 and grip the wall 16 of the faucet between it and the adjacent end of the tubing. The free end 17 of the spring is turned outwardly so as to permit the tube to be readily positioned onto a faucet, the spring serving to support the discharge end 18 of the tube in a vertical position whereby it may readily serve as a convenient water supply from which to drink. 75

By forming the tubing of a diameter less than the discharge opening in the faucet but a small portion of the water is forced through the tubing and therefore will flow with diminished force from the discharge end 80 thereof.

In some instances, it is found of advantage to also provide a cup member 19 with a tubular neck portion 20 to set either inside or over the outside end of the discharge end of the tubing, the cup serving when partially filled with water to modify the discharging force of the stream to be consumed. 85

In some instances, instead of arranging the spring in the form illustrated in Figures 1 and 2, I may form the same as illustrated in Figure 4, in which it is in the shape of a loop 22 to grip the inner wall of the faucet 23 and so bind and support the drinking end of the tubing 24 in operating position. 90

My improved sanitary drinking device is extremely simple and inexpensive in construction, and may be readily carried in the pocket of the user. The cup member which is applied to this tubing is formed very thin and can also be readily carried about in the pocket of the user. The spring of the tubing is so arranged that the device may be instantly attached to a faucet to be supported in operating position and as quickly detached after a 100 sufficient quantity of water has been consumed to quench the thirst.

The foregoing description is directed solely towards the construction illustrated, but I desire it to be understood that I reserve the 110 privilege of resorting to all the mechanical changes to which the device is susceptible,

the invention being defined and limited only by the terms of the appended claims.

I claim:

1. In combination with a water faucet, a drinking attachment comprising a short length of rigid tubing having its end portions set at an angle to the axis of its body portion, the diameter of one end portion of the tubing being less than the inner diameter of the faucet and extending inside the faucet, and having resilient means to support the said inserted end portion against one side of the faucet.
2. A drinking attachment for water faucets, comprising a rigid U-shaped tubing having one end for insertion into the outlet of a faucet of larger internal diameter, and a spring on said end to grip the faucet and support the opposite end of the tubing in drinking position.

3. A drinking attachment for water faucets, comprising a rigid U-shaped tubing having one end of a size to extend into a faucet of larger internal diameter, and a spring finger on the outside of said end positioned to grip the wall of the faucet between it and the inwardly-extending portion of the tubing to support the discharge end of the tubing in operating position.

4. A drinking attachment for water faucets, comprising a rigid U-shaped tube having one end for insertion into the outlet of a faucet of larger internal diameter, a spring on said end to grip the faucet and support the opposite end of the tubing in drinking position, and a readily detachable drinking cup supported on the discharge end of the tubing and into which the discharge water flows.

In testimony whereof I affix my signature.

JOSEPH ROSAY.
